Werner Neuhs.

by Geo. H. Gibbitts, Attorney.

UNITED STATES PATENT OFFICE.

WERNER NEUHS, OF CLEVELAND, OHIO, ASSIGNOR OF ONE-HALF TO
WILLIAM E. KRUMSOY, OF SAME PLACE.

BAKER'S OVEN.

SPECIFICATION forming part of Letters Patent No. 608,068, dated July 26, 1898.

Application filed August 6, 1897. Serial No. 647,374. (No model.)

To all whom it may concern:

Be it known that I, WERNER NEUHS, a citizen of the United States, residing at Cleveland, in the county of Cuyahoga and State of Ohio, have invented certain new and useful Improvements in Bakers' Ovens, of which the following is a specification.

This invention relates to bakers' ovens; and it consists in the new construction and combinations of parts adapted for the purpose, substantially as hereinafter described, and pointed out in the claim.

In the accompanying drawings, Figure 1 is a front elevation of the new baker's oven. Fig. 2 is a longitudinal section on line 2 2 on Fig. 1. Fig. 3 is a horizontal section on line 3 3 on Fig. 2. Fig. 4 is a horizontal section on line 4 4 on Fig. 2. Fig. 5 is a cross-section on line 5 5 on Fig. 2. Fig. 6 is a cross-section on line 6 6 on Fig. 2.

A represents a base of brickwork, having a fireplace A' at each side and side walls A'' and a back wall in which is a chimney-flue, with passages leading into it. B is a sheet-metal plate lying over said base and covering both fireplaces. C is another sheet-metal plate supported in the side walls a little distance above the said plate B, which forms a chamber or space between said plates. This plate C forms the bottom to the oven and has a flooring of tile. D is a third sheet-metal plate supported on I-bars between the side walls A''. This forms the top of the oven proper. The front end of the oven is provided with a door F and the back end closed by an end plate. D' is a fourth metal plate, also supported on cross I-bars between the side walls A'' a little distance above the said third plate D, thus forming a chamber or space E over the oven. On the top of said fourth plate is placed a quantity of sand. In the masonry at the back of the oven are made vertical flues or passages E', connecting the back ends of the fireplace-flues with the space over the oven, as shown, through

which the heat is conveyed to and over the top of the oven in the direction indicated by the arrows. At each side of the front opening to the oven are also provided vertical passages G G, connecting the space over the oven with the space between the plates B and C, through which the heat is further conveyed under the oven, as shown by the arrows. In the back end wall at the end of said space B are made holes h h h for conveying the heat into the flues I I and J J into the chimney. Thus the heat is carried entirely around the oven and a uniformity of heat is produced.

K is a water-tank arranged beside the oven, having a pipe L fixed in one of the fireplaces for heating water, the top of the tank having pipe connection with the oven, adapted for injecting steam into the oven at such times as may be required.

Having described my invention, I claim—

In a baker's oven, a base A of masonry, a fireplace A' at each side of said base with side walls A'', a sheet-metal plate B over said base and fireplaces, a second plate C over said plate B forming a space between said plates, a third plate D supported on cross-bars between the side walls, the chamber between said plates C and D forming the oven proper, a fourth plate D' supported on cross-bars between the side walls and covered with sand, the space between said plates D D' forming a space over the oven, a door F to the front of the oven, a back end wall, passages E E in said end wall connecting the fireplaces with the space D, front passages G G connecting space D with the space B and the holes h h h connecting the space B with the flues I I J J into the chimney, all constructed to operate as and for the purpose specified.

WERNER NEUHS.
